FLOOR SWEEPER

Truman B. Funk, Jackson, Mich., assignor to
 "Yard-Man," Inc., Jackson, Mich., a corpora-
 tion of Michigan

Application January 16, 1939, Serial No. 251,056

3 Claims. (Cl. 15—49)

This invention relates to floor sweepers and more particularly to floor sweepers designed for use on uncarpeted floors, such as in factories, dance halls, gymnasiums and the like.

In the past, sweepers for uncarpeted floors have been unsatisfactory because of their failure to sweep clean. In an attempt to provide a clean sweeping sweeper, the dust catching apron has been placed in front of a rotary brush so that the brush theoretically catches all dirt that is passed over by the sweeper, and, incidentally, the apron, which must be spaced from the floor in order to permit the dirt to pass under it. However, in practice, this type of sweeper has not been satisfactory. The present invention contemplates providing an adjustable rubber apron behind a rotary brush which rotates in the same direction as the ground wheels, the adjustment permitting the disposition of the apron in the proper contacting relation with the floor being swept in order to permit the maximum amount of dirt to be picked up while at the same time providing a minimum drag.

An object of the invention is to provide a floor sweeper having an adjustable rubber apron disposed behind a rotary brush.

Another object of the invention is to provide a floor sweeper having a rotary brush revolving in the same direction as the ground wheels.

A further object of the invention is to provide a floor sweeper having the dirt catching apron behind and a dirt receptacle in front of a rotary brush.

A still further object of the invention is to provide a floor sweeper having deflectors for deflecting the dirt picked up by a rotary brush into a dirt receptacle and to deflect the draft created by the rotation of the brush toward the dirt catching apron.

These and other objects will be apparent from the following specification when taken with the accompanying drawings, in which

Fig. 1 is a vertical section of one form of the invention.

Fig. 2 is a perspective view of the same.

Fig. 3 is a vertical section showing the rear caster.

Fig. 4 is a side elevation showing another form of the invention.

Fig. 5 is a partial section on the line V—V of Fig. 4.

Fig. 6 is a section on the line VI—VI of Fig. 5, and

Fig. 7 is a sectional detail taken on the line VII—VII of Fig. 1.

Referring particularly to the drawings, the reference characters 1 indicate the side frame members of the floor sweeper, over the rear and upper portion of which is disclosed a casing 2, which preferably is of sheet metal and is secured to the edges of the side frame members 1 in some suitable manner. The side frame members 1 preferably are cast and bowed outwardly in the central portion thereof as shown particularly in Figs. 5 and 7. Intermediate the frame members 1 the casing 2 is recessed, as shown particularly in dotted outline in Figs. 1 and 7, providing a dirt deflecting surface 3. The frame members 1 have integral therewith forwardly extending arms 4, in which are disposed slots 5. Disposed in the slots 5 are bolts 6, on which are mounted the ground wheels 7. Nuts 8 are employed to clamp the bolts 6 in the slots 5 and to adjust them longitudinally of the slots 5 for the purpose of tightening the belts 9 in V-grooves 10 in the peripheries of the ground wheels 7.

The belts 9 are in driving engagement with pulleys 11 mounted on the ends of a shaft 12, the shaft 12 mounting a rotary brush 13. The depressed surface 3 of the casing 2 at the rear portion thereof is arcuate in form and of substantially the same radius as the rotary brush 13, the periphery of the brush 13 being contiguous to the rear portion of the surface 3. The brush 13 is of sufficient width so that the extreme side portions adjacent the periphery thereof are in engagement with the side frames 1 as shown particularly in Fig. 7. The fact that only the peripheral portions of the brush 13 are in engagement with the side frames 1 is due to the arcuate configuration of the side frames 1. The result of this construction is that any dirt picked up by the brush and carried around the dirt deflecting surface 3 is retained against falling downwardly as it would were there a space between the ends of the brush 13 and the side frames 1. At the lower rear end of the casing 2 is mounted an apron 18 preferably of flexible molded rubber and arranged to be in contiguous relation with the surface being swept.

Extending rearwardly of the sweeper and integral with the side frame members 1 are arms 19, between which is connected a bar 20. Midway between the ends of the bar 20 is mounted a caster 21, shown in Fig. 6, having a freely rotatable ground wheel 22. Vertical adjustment of the caster 21 to adjust the position of the apron 18 and the rotary brush 13 with respect to the surface being swept is provided by an externally threaded sleeve 23, in which the shank 24 of the

caster 21 is snugly retained. The sleeve 23 is threaded into the bar 20 and is provided at the upper end thereof with a hexagonal or square portion 25. Vertical adjustment of the caster 21 is obtained by applying a wrench to the hexagonal or square portion 25 of the sleeve 23 and rotating the same, the adjustment being fixed by tightening a locking nut 26 against the bar 20.

The dirt receptacle 27 for the sweeper is shown particularly in Figs. 1 and 2 and is in the form of a sheet metal box having a portion of the top and portion of the upper rear side cut away. Each side of the receptacle 27 is provided with a trunion 28 arranged for disposition in open topped bearing members 29 integral with the arms 4. The side frames 1 are provided with wings 30 for overlapping engagement with the sides of the dirt receptacle 27 to provide a seal against the escape of dirt.

Between the side frames 1 is connected a transverse angle bar member 35, shown in Fig. 1, one leg thereof being substantially vertical and the other leg thereof being inclined upwardly toward the rear, the member 35 being disposed in front of the brush 13. To the surface of the upper leg of the bar 35 is connected a transversely extending plate 36, which projects from adjacent the periphery of the brush 13 to within the receptacle 27 for the purpose of directing dirt swept by the brush 13 into the receptacle 27. A deflecting plate 37, which is inclined downwardly and rearwardly in such a manner as to direct the draft created by the rotation of the brush 13 rearwardly toward the apron 18, is connected to the vertical leg of the member 35.

Disposed over the opening in the upper portion of the receptacle 27 is a dirt filter 38 in the form of a fabric bag readily pervious to air but not to dust. The bottom side of the bag is open and is supported by a frame having a peripheral member 39 and a plurality of transverse members 40. Connected to the upper portion of each side frame member 1 is an arm 41 having a curved forwardly and downwardly extending finger 42. The fingers 42 extend through suitable openings in the lower rear edge of the filter 38, as shown particularly in Figs. 1 and 2, and provide, with an upwardly projecting portion 43 of the surface 3 at the front edge thereof, a hinge. It will be understood that the arms 41 are connected to the frame members 1 by screws or the like 44 in order that they may be removed to permit the connection of the filter 38 to the sweeper. By virtue of the pivotal connection provided by the portion 43 and the hinges 42, the filter 38 may be pivoted rearwardly, as shown in the exploded view in Fig. 2.

As shown particularly in Fig. 2, the upper side edges of the receptacle 27 are provided with upwardly and inwardly extending wings 48, and the front upper edge of the receptacle 27 is provided with an upwardly and rearwardly extending wing 49. When the receptacle 27 is assembled on the sweeper by disposing the trunions 28 in the upwardly opening bearings 29, the front edge thereof bears against the deflecting plate 37, the wings 30 overlap the side portions of the side opening thereof, as above explained, and the filter 38 fits over the wings 48 and 49, as shown in Fig. 1.

Pivoted to the side frame members 1 is a suitable handle 50, the pivotal movement of which is limited by pins 51 integral with the side frame members 1. In use, the sweeper is pushed forwardly by an operator holding the handle 50.

In operation, the caster 21 is adjusted until the apron 18 and the brush 13 are disposed in the correct relation to the floor to be swept. It is to be understood that the apron 18 should just touch the floor but should not bear against the same with sufficient force to exert an undesirable drag on the operation of the sweeper. As the sweeper is moved forwardly, the ground wheels 7 rotate, thereby driving the rotary brush 13 by the belts 9. It will be clear from the drawings that the brush 13 rotates in the same direction as the ground wheels and brushes dirt from the floor against the apron 18, which deflects it upwardly to the surface 3, providing a continuation of the surface of the apron 18. The rotation of the brush 13 carries the dirt upwardly and over it along the surface 3 and directs it forwardly into the receptacle 27. The deflector 37 serves to prevent the dirt which has been swept up from dropping downwardly in front of the brush, and directs it directly into the receptacle 27. As there is some draft provided by the rotation of the brush 13, the deflector 37 directs the draft rearwardly toward the apron 18 so that it is utilized in the cleaning of the floor rather than serving to spread the dirt and dust being swept laterally of the sweeper. As the dirt is directed into the receptacle 27, it will be understood that there is some air pressure developed therein due to the rotation of the brush 13. For this reason the air filter 38 has been provided to permit the escape of the air in the receptacle 27, yet preventing the escape of dust and dirt. In operation, the filter 38 will assume a position somewhat similar to that disclosed in Fig. 1, that is, extended. However, when the sweeper is not in operation, the filter 38 will collapse and rest against the transverse wires 40 in the bottom framework thereof.

Another form of my invention is disclosed in Figs. 4, 5 and 6. In this form of the invention a separate adjustment has been provided for the apron 18. The apron 18, as shown particularly in Fig. 6, has a sheet metal mounting member 55, which is wrapped about a square shaft 56. The shaft 56 has the ends 57 thereof turned down into a cylindrical form and are disposed in bores 58 in arms 59 removably secured to lugs 60 integral with the side frames 1.

About one end of the shaft 56, but inwardly from the cylindrical portion 57, is a sleeve 62, to which is secured an upwardly extending lever 63 of flat spring metal. Struck inwardly from the lever 63 is a detent 64 for engagement with an arcuate toothed lug 65, which is integral with a side frame 1. The spring lever 63 is biased so as to urge the detent 64 into engagement with the toothed lug 65. Adjustment of the apron 18 relatively to the floor being swept is then obtained by rotating the shaft 56 in the bores 58 by means of the lever 63. Any adjustment thus obtained is maintained by the detent 64 resting between two of the teeth of the toothed lug 65.

An advantage of the construction disclosed in Figs. 4, 5 and 6 is that the apron 18 may be adjusted relatively to the floor being swept independently of the brush 13, the adjustment of which with respect to the floor in this case is accomplished by adjusting the caster 21. It is found in actual practice that the adjustment of the apron 18 must be very exact in order to secure good sweeping. Therefore, since the apron 18 is in contact with the floor being swept during operation and therefor wears off, the adjustment of the same from time to time is very desirable.

While the apron 18 has been disclosed as composed of rubber, it of course may be composed of other substances. However, I have found that the best results are obtained by using rubber. When the term "rubber" is used in the specification, it is to be understood that I do not intend to limit myself specifically to rubber. It is contemplated that the term include artificial rubber, rubber substitute, or any other flexible material having satisfactory wearing qualities and the ability to be flatly disposed upon the surface being cleaned for a reasonable length of service. In practice, the apron 18 is provided with a horizontal foot portion 18', which enables the apron to keep out of cracks. The adjustment of the apron 18 through the handle 63 has the tendency of placing more pressure upon the toe or forward edge portion 18'' than on the heel 18''', which has the effect of causing the foot portion to be disposed flatly upon the surface being swept. As shown particularly in dotted outline in Fig. 6, the apron 18 is originally molded flat, but when it is in contact with the floor when attached to the sweeper, as shown in full line in Fig. 6, it assumes an arcuate configuration. The arcuate state of the apron 18 is regulated through the adjustment of the lever 63 and the height of the caster 21 to obtain the most efficient operation of the apron 18. In practice, the apron 18 is adjusted so as to sweep clean with a minimum amount of floor pressure upon the foot 18' to reduce wear and resistance to movement of the sweeper. As the apron 18 and brush 13 wear in service, adjustment of the lever 63 and caster 21 will be required.

From consideration of Fig. 1 it will be observed that the casing embracing the rotary brush defines a volute conduit, along which dirt and air currents are directed through approximately 270° of the circumference of the brush. The deflector 36 acts to direct the air currents created by the brush during 270° of its rotation and the dirt carried over thereby into the receptacle 27. As shown, a portion of the deflector 36' extends into the receptacle 27, creating below the same a dead air space in the receptacle 27, in which the dirt may settle. The design of the receptacle 27 below the level of the deflector 36' is such as to eliminate to a great extent all eddy currents and permitting the dirt to readily settle into the receptacle. The location of the air escape directly above this dead air space and adjacent the discharge inlet into the receptacle 27 also acts to facilitate the prompt settling out of the dirt in the receptacle, eliminating any tendency for the dirt to be blown around and escape. From the point of air discharge provided for by the deflectors 36 through approximately 90° of the circumference of the brush, air currents are created which, assisted by the deflector 37, act in a direction of initial dirt movement, thus facilitating the

elevation of dirt upon the apron 18 in its movement toward the receptacle. It has been found that the provision of the deflectors 36 and 37 has eliminated any tendency for the dirt to dribble down from above and to escape being picked up by the rotary brush.

Having thus described my invention, what I desire to secure by Letters Patent and claim is:

1. A sweeper of the character described, comprising ground wheels, a rotary cylindrical brush, means to rotate said brush in the same direction as said ground wheels, a dirt catching apron behind said brush, means extending laterally of said sweeper pivotally mounting said apron, means to adjust the apron about said mounting means into contiguous relation with the surface being swept, a dirt receptacle in front of said brush having an opening above the center line of said brush and spaced therefrom, a curved surface behind and over said brush forming an extension of said apron to direct dirt swept by said brush and picked up by said apron into said receptacle, a substantially flat deflecting surface extending from the lower edge of said opening rearwardly into contiguous relation with said brush, bridging the space between said brush and said opening, to direct dirt carried by said brush and directed by said first named surface into said opening, and a rearwardly inclined deflecting surface in front of said brush for deflecting the draft created by said brush toward said apron.
2. In a floor sweeper of the character wherein a cylindrical brush rotates against an apron to lift dirt from a floor, a flexible apron having a web portion and a forward toe portion, which in operation is pushed along the floor, a foot portion extending rearwardly along the floor being swept from said toe portion and being of substantial width, said web portion being deflected into arcuate shape through contact of said toe and foot portions with the floor and being supported through said toe and foot portions.
3. In a floor sweeper, a rotary cylindrical brush, means rotating said brush to move the lower active portion thereof in the opposite direction to bodily movement of the sweeper, a casing embracing the periphery of said brush to define with the brush a conduit for the discharge of dirt and air through approximately 270° of the circumference of said brush, a dirt container having an opening disposed at the point of discharge of said conduit, and an air current deflecting structure located adjacent said discharge and contiguous with the circumference of said brush for directing air currents created during the remaining 90° of circumference of said brush toward the point of initial dirt movement through said conduit, said deflecting structure comprising a transverse, substantially flat plate extending downwardly and rearwardly.

TRUMAN B. FUNK.
